UNITED STATES PATENT OFFICE.

ARTHUR T. HAGEN AND DANIEL M. COOPER, OF ROCHESTER, NEW YORK.

STARCHING-MACHINE.

SPECIFICATION forming part of Letters Patent No. 606,411, dated June 28, 1898.

Application filed June 21, 1897. Serial No. 641,612. (No model.)

To all whom it may concern:

Be it known that we, ARTHUR T. HAGEN and DANIEL M. COOPER, of Rochester, in the county of Monroe and State of New York, have invented certain new and useful Improvements in Starching-Machines; and we do hereby declare the following to be a full, clear, and exact description of the same, reference being had to the accompanying drawings, forming a part of this specification, and to the reference-numerals marked thereon.

Our present invention has for its object to provide an improved machine for use in laundries, and particularly for applying starch or other liquids to garments preparatory to ironing them, and is adapted for starching bosoms of shirts or similar articles composed of several plies, whereby the starch or liquid will be applied and worked into the garment and the latter will be stretched and so operated upon that any wrinkles will be removed and the article may then be ironed in any of the ordinary types of ironing-machines. The machine is also well adapted for starching other garments or articles having two or more plies which when ironed must be in close and intimate contact.

To these and other ends the invention consists in certain improvements, the novel features being pointed out particularly in the claims at the end of this specification.

In the accompanying drawings, Figure 1 is a side elevation of a machine constructed in accordance with our invention; Fig. 2, a front view of the same with a portion of the rocking frame broken away to show the construction more clearly; Fig. 3, a plan view; Fig. 4, a longitudinal sectional view showing the controlling-lever in elevation; Fig. 5, a sectional view on the line xx of Fig. 4; Fig. 6, a sectional view on the line yy of Fig. 3.

Similar reference-numerals in the several figures indicate similar parts.

The main frame of the machine may be of any suitable construction, the preferred form embodying the sides 11, connected by a suitable brace 2 at the bottom and at the top by a cross-frame 3, upon which is supported the receptacle 4 for containing starch or other liquid to be applied to the goods, and upon this cross-frame 3 is also formed or secured a hollow arm or casting 5, projecting to the

front of the machine and to which is secured the curved work support or table 6. The interior of the frame constitutes a steam-chamber 55 provided with inlet and exit pipes 7, whereby the starch may be heated and also heat will be communicated to the work support or table 6.

8 indicates a driving-shaft supported in 60 bearings in the side frames, having the belt-pulleys 9 and 10 at one end and having also splined upon it a movable clutch-section 11 in the form of a shiftable gear, adapted to coöperate with another clutch-section 12 in 65 the form of a gear, secured rigidly upon a shaft 13, also mounted in bearings in the frame.

14 indicates a shifting-lever pivoted in suitable brackets 15 on one of the side frames and having its end 16 projecting laterally of the machine and in position to be operated upon by the end of the foot lever or treadle 17, pivoted loosely upon a shaft 18, extending between the side frames. This shaft 18 may be 75 either rigid with the frames or capable of oscillation in suitable bearings therein, as desired. Also mounted upon the shaft 18 is a rocking or oscillating frame embodying a lower portion 19 and upwardly-extending 80 arms 20, upon which are mounted extensible arms or rods 21, in the upper ends of which is mounted a shaft 22, carrying the starch-applying roller 23. The upper arms 21 of this frame extend into sockets or recesses formed 85 in the rods 20, and springs 24 are arranged between these sections, operating to draw down the shaft 22, carrying the starch-roller, and hold the latter in elastic contact with the work, as will be described. The frame 19 is also 90 provided with a central arm 25, having a curved slot 26, in which operates a pin or roller 27, connected to the bifurcated lower end of a pitman 28, the upper end of the latter being journaled to a crank 29 on the cross-shaft 13, as shown particularly in Figs. 2 and 4.

30 indicates a shaft journaled in the frame and having at its central portion an arm or extension 31, connected by links 32 with the ends of the pin or roller 27, said shaft having also an operating handle or lever 33, arranged at the side of the machine and provided with a manually-operated catch or dog 34, coöoperating with suitable notches formed

in a segment 35, and a spring 36, connected to the end of the arm 31 and to the frame, tends to assist in rotating the shaft 30 when the handle is moved by the operator, as will be described.

The arm 25, connected to the oscillating roller-carrying frame, is arranged in such position relative to the end 16 of the clutch-operating lever that when the parts are in the 10 position shown in Fig. 4 the clutch-sections are held by said arm disengaged and the machine is at rest. When, however, it is desired that the starch-carrying roller shall be moved across the bed or table 6, the operator moves 15 the treadle 17 down, a cross-bar 17^x thereon raising the arm 25 on the oscillating frame and tipping said frame forward until the starch-carrying roller is moved out of the starch-receptacle and upon the end of the table, and 20 at this time the rear end of the treadle 17 engages the clutch-shifting lever 16, connecting the driving-shaft with the shaft 13 and rotating the latter as the driving-shaft rotates. The crank and pitman 28, operating on the 25 roller or pin 27, cause the oscillating frame to be rocked and the starching-roller moved back and forth across the bed. The amount of the movement of the frame and roller is controlled by the manipulation of the handle 33, which 30 through the devices described moves the pin or roller 27 in the slot 26 of the rocking frame nearer to or farther from the point of oscillation—*i. e.*, the shaft 18—from which it will be seen that the length of movement of the 35 starch-carrying roller may be controlled as desired and the article upon the table, whether long or short, may be thoroughly saturated with starch and any wrinkles removed by the roller. When it is desired to arrest the 40 operation of the machine, the handle 33 is returned to the position shown in full lines and pressure on the treadle 17 is released, allowing the arm 25 on the oscillating frame to drop back and engage the end 16 of the clutch-lever 45 and disengage the clutch.

It will be understood that while the machine is in operation the treadle 17 holds the arm 25 of the oscillating frame out of engagement with the clutch-operating lever 16.

50 The starch-roller 23 may be of any suitable construction that will carry a quantity of starch over upon the garment or article operated upon and force it into the meshes; but we prefer to provide said roller with a covering 55 40 of india-rubber provided with cells or pockets in its surface, as shown particularly in Fig. 5, as we find that the cells or pockets will carry a sufficient amount of starch and the slight compression of the ridges between the 60 cells will cause the contents thereof to be forced through the goods operated upon. The movement of the roller over the table or support causes its rotation; but in order that when it is arrested in the starch-receptacle it 65 may be rotated to fill the pockets and agitate the starch as well we provide the end of the shaft 22 with a pulley 41, adapted to be oper-

ated upon by a belt 42, driven from the shaft 8 and extending over a tightener-pulley 43, mounted upon the end of a weighted lever 44, 70 as shown particularly in Figs. 1 and 2.

45 45 indicate guides or brackets secured to the side frame and forming ways to guide the roller from the starch-receptacle to the end of the table, the pulley 41 engaging one of said ways, while at the opposite end of the shaft is provided a roller 46 for coöperating with the other bracket. The forward end of the starch-receptacle is provided with a pivoted flap or plate 47, and connected to the ends of this flap 80 are bell-crank levers or arms 48, with which the shaft 22 (or spacing-collars 39 on said shaft) coöperates to tilt the flap 47 down to the position shown in dotted lines in Fig. 6, when the roller is moved out over the table and the 85 spacing-collars 39 engage the lower arms of the bell-cranks and serve to return said flap to the position shown in full lines in said figure and maintain it in this position while the roller is within the receptacle.

49 indicates a small apron or strip of material attached to the flap and extending into the receptacle for preventing the starch from spilling out of the latter.

The collars or sleeves 39 serve to space the 95 roller 23 properly upon the shaft 22, and they are provided with protecting-flanges 38.

50 indicates a shield for preventing goods from becoming caught in the operating parts of the machine.

The machine as a whole is very simple and easily operated, the operator being enabled to apply either a small or large quantity of starch to an article and to rub or work it into it, and this whether or not the whole of the work support or table is covered by it, this being particularly advantageous in starching shirt-bosoms which vary in length, as it is only necessary to apply the starch to the bosom without starching the body. When, the treadle 17 alone is operated, the starch-roller is removed from the receptacle and is given its minimum oscillating movement over the work support or bed as the pitman 28 engages the oscillating frame at a distant point from its oscillating center, and the lever 33 enables the extent of movement over the work-table to be regulated. The upwardly-extending portion of the slot 26 in the arm 25 of the oscillating frame is for the purpose of permitting the 110 disconnection of the clutch by the frame when pressure is removed from the treadle, the frame then dropping and actuating the clutch.

While we have shown a starting and stopping device in the form of a positive clutch, 115 it will be understood that any other equivalent device could be substituted, such as a friction-clutch or a belt-shifter, if desired.

The machine could with slight modifications be adapted for other purposes than that 120 of applying starch to garments; but we find it particularly adapted for starching the bosoms of shirts, as the starch is worked into the garment and the curved support and the

roller moving over it takes out wrinkles and lays the plies flat and in contact.

We claim as our invention—

1. The combination with the work-support, 5 of the oscillatory frame, the roller on the frame moving over the support and coöperating therewith, a rotary shaft having a crank of determinate throw, and adjustable connections under the control of the operator ar- 10 ranged between said crank and the frame for varying the extent of movement of the roller over the support, substantially as described.

2. The combination with the work-support and the starch-receptacle at the end thereof, 15 of the starch-roller movable over the support and arranged to coöperate with the starch-receptacle, power devices for actuating the roller back and forth over the support and into and out of coöperative relation with the 20 receptacle, and means controlled by the operator for varying the extent of movement of the roller over the support while being operated upon by the power devices.

3. The combination with the work-support, 25 the starch-receptacle at the end thereof, the roller movable over the support and coöperating with the receptacle, and the oscillating frame on which the roller is mounted, of an arm on the frame, a rotary crank-shaft, a 30 pitman connected thereto, and means controlled by the operator for varying the connection between the pitman and arm to vary the movement of the roller over the support.

4. The combination with the work-support, 35 a starch-receptacle at one end thereof, an oscillating frame, and a starch-carrying device thereon movable over the support, of a rotary crank-shaft, an arm on the oscillating frame, and adjustable connections between said arm 40 and crank-shaft for varying the extent of oscillation of the frame, substantially as described.

5. The combination with the work-support, 45 the oscillating frame, and the roller mounted thereon, of the slotted arm on the frame, the rotary crank-shaft, the pitman having the pin operating in the slot in the arm, and means for adjusting said pin in the slot, substantially as described.

50 6. The combination with the work-support, the pivoted oscillating frame having the actuating-arm, the spring-mounted roller on the frame, of the rotary shaft having the crank, and adjustable connections between said 55 crank and the arm on the frame for varying the extent of the oscillations of the latter, substantially as described.

7. The combination with the work-support, 60 the oscillating frame having the actuating-arm, and the roller on the frame, of the rotary shaft, the crank thereon, a pitman connected to the crank and operating on the actuating-arm, and the controlling-lever connected to the pitman and controlling the connection between the latter and the arm, substantially as described.

8. The combination with the work-support,

the oscillating frame, and the operating device on the latter movable over the support, 70 of a rotary shaft, adjustable connections between said shaft and the oscillating frame, whereby the extent of movement of the frame may be controlled, a starting and stopping device for the shaft, such as a clutch, connections between said starting and stopping device and the frame whereby the latter may operate the former to arrest the machine, and a starting-arm controlling the movement of the frame relatively to said device, and co- 75 operating with the starting mechanism to start the machine when moved in one direction, substantially as described.

9. The combination with the work-support, the oscillating frame, and the operating device on the latter movable over the support, 80 of a rotary shaft, connections between said shaft and the oscillating frame, a clutch device for controlling said shaft actuated in a direction by the frame to arrest the shaft, a starting-arm coöperating with the clutch de- 85 vice to start the machine and preventing the frame from actuating the clutch device when moved in one direction and permitting the frame to release the clutch when operated in the opposite direction, substantially as de- 90 scribed.

10. The combination with the work-support, the oscillating frame, and the operating device on the latter movable over the support, 95 and the arm on the frame having the curved 100 slot, of the rotary shaft, the pitman having the pin operating in the slot of the arm, the lever and link controlling the pin, a clutch device for controlling the shaft, the treadle operating the frame, and connections between 105 the treadle, arm and clutch device for starting the machine by the movement of the treadle in one direction and permitting its arrest when the treadle is released, substantially as described. 110

11. The combination with the work-support, the oscillating frame, and the operating device on the latter movable over the support, 115 of a rotary shaft, connections between the latter and the oscillating frame, a clutch for controlling the rotation of the shaft, connections between it and the frame for disengaging the clutch by the movement of the latter, a starting-arm coöperating with the clutch to engage it, and also coöperating with and limiting the movement of the frame, thereby preventing the disengagement of the clutch, substantially as described.

12. The combination with the work-support, the oscillating frame, and the operating 125 device on the latter movable over the support, of a driving-shaft, and connections between it and the oscillating frame for actuating the latter, a starting and stopping mechanism, such as a clutch, arranged between the driving-shaft and the oscillating frame, a lever for operating said starting and stopping device engaged by the oscillating frame, and a treadle for holding the frame out of contact 130

with the lever and also operating said lever in one direction, substantially as described.

13. In a starching-machine, the combination with the smooth work-support upon which the articles may be adjusted, and a starch-receptacle at one end thereof, the surface of said support being accessible to the operator during the operation so that the article may be readily adjusted thereon, of a horizontally movable frame, a starch-carrying roller mounted thereon movable over the support and adapted to enter the starch-receptacle at one extreme of its movement, substantially as described.

14. In a starching-machine, the combination with the work-support, the surface of which is readily accessible and a starch-receptacle at one end thereof, of a movable frame, a starch-carrying roller mounted thereon and adapted to travel over the support and enter the receptacle, power devices for oscillating the frame, and controlling devices for varying the extent of movement of the frame while oscillating, substantially as described.

15. In a starching-machine, the combination with the work-support, and a starch-receptacle at one end thereof, of a movable frame, a starch-carrying roller mounted thereon and adapted to travel over the support and enter the receptacle, and means for rotating the roller independently of its movement over the support and while within the receptacle, substantially as described.

16. In a starching-machine, the combination with the work-support, and a starch-receptacle at one end thereof, of a movable frame, a starch-carrying roller mounted thereon and adapted to travel over the support and enter the receptacle, a pulley on the roller, and a friction driving device arranged in proximity to the receptacle for engaging the roller when the latter is in the receptacle, substantially as described.

17. In a starching-machine, the combination with the work-support, and the starch-receptacle at one end thereof, of the movable frame, the roller carried thereby movable over the support and adapted to enter the starch-receptacle, and the pivoted flap on the receptacle with which the roller co-operates, substantially as described.

18. In a starching-machine, the combination with the work-support and the starch-receptacle at one end thereof, of the movable frame, the roller carried thereby movable over the support and adapted to enter the starch-receptacle, the pivoted flap at the end of the receptacle having the rock-arms at the ends, substantially as described.

19. In a starching-machine, the combination with the work-support and the starch-receptacle at the end thereof, of the movable frame, the roller carried thereby movable over the support and adapted to enter the receptacle, the pulley on the roller, the traveling belt and the belt-tightener, substantially as described.

20. The combination with the work-support, the surface of which is readily accessible and the starch-receptacle at the end thereof, of the movable frame, the roller mounted on the frame having the elastic cellular surface, devices under the control of the operator for actuating the roller over the surface of the support or into co-operative relation with the receptacle.

21. The combination with the curved work-support, the surface of which is readily accessible to the operator, of the pivoted swinging frame, the roller mounted on the frame and having the elastic cellular surface, a starch-receptacle at the end of the work-support, devices under the control of the operator for operating the roller over the support or into co-operative relation with the receptacle.

22. The combination with the hollow frame having the hollow arm, the work-support on the arm, and the starch-receptacle on the frame at the end of the work-support, of the movable frame and the starch-roller carried thereby and movable over the work-support and into and out of the receptacle, substantially as described.

23. The combination with the curved work-support, and the receptacle at the end thereof, of the rocking frame having the spring-operated telescoping arms, the roller mounted on said frame, and means for operating said roller back and forth over the support and into and out of the receptacle, substantially as described.

24. The combination with the work-support and the starch-carrying roller, one of which is movable, and the starch-receptacle with which the roller co-operates, of power devices for operating the movable part and causing the co-operation of the roller and receptacle and means controlled by the operator for varying the extent of movement of the movable part while the power devices are in operation.
